CLAIM

The ornamental design for a kangaroo carrying bag, as
shown and described.

DESCRIPTION

FIG. 1 is a perspective view from above, the front and
one side of a kangaroo carrying bag showing my new
design;

FIG. 2 is a perspective thereof from the rear and other
side;

FIG. 3 is a front perspective view of a second embodi-
ment in the form of a toy animal figure;

FIG. 4 is a rear perspective thereof; and

FIG. 5 is a front perspective view of a third embodi-
ment thereof.

The opposite side of FIG. 5 is the same as FIG. 2.

FIG. 1

FIG. 2

FIG. 5
